H. ROWNTREE.

CHAIR.

APPLICATION FILED SEPT. 1, 1917.

1,354,133.

Patented Sept. 28, 1920.

Inventor
Harold Rowntree
By his accy Samuel E. Darby

UNITED STATES PATENT OFFICE.

HAROLD ROWNTREE, OF KENILWORTH, ILLINOIS, ASSIGNOR TO NATIONAL PNEUMATIC COMPANY, OF NEW YORK, N. Y., A CORPORATION OF WEST VIRGINIA.

CHAIR.

1,354,133.

Specification of Letters Patent. Patented Sept. 28, 1920.

Application filed September 1, 1917. Serial No. 189,897.

To all whom it may concern:

Be it known that I, HAROLD ROWNTREE, a citizen of the United States, residing at Kenilworth, county of Cook, State of Illinois, have made a certain new and useful Invention in Chairs, of which the following is a specification.

This invention relates to chairs, settees, and the like.

10 The object of the invention is to provide a chair which is simple in structure, durable, and economical of manufacture.

A further object of the invention is to provide a chair, settee, or the like, which 15 may be tilted backwardly to any desired degree for convenience or comfort.

A further object of the invention is to provide means for preventing a chair, settee, or the like, from overturning due to the 20 backwardly tilting position thereof.

A further object of the invention is to provide a chair which may be readily tilted from one position to another by means of the foot without necessitating excessive 25 manual labor or inconvenience of being compelled to stoop over to manipulate the tilting mechanism.

Further objects of the invention will appear more fully hereinafter.

30 The invention consists substantially in the construction, combination, location and relative arrangement of parts, all as will be more fully hereinafter set forth, as shown by the accompanying drawing, and finally 35 pointed out in the appended claims.

Referring to the drawing:—

Figure 1 is a bottom view of a chair embodying my invention.

Fig. 2 is a view in section taken on the 40 line 2, 2, Fig. 1, looking in the direction of the arrows.

Fig. 3 is a sectional view taken on the line 3, 3, Fig. 2, looking in the direction of the arrows.

45 Fig. 4 is a sectional view taken on the line 4, 4, Fig. 1, and looking in the direction of the arrows.

Fig. 5 is an enlarged detailed view inverted of the latch mechanism employed in accordance with my invention.

The same part is designated by the same reference numeral wherever it occurs throughout the several views.

55 It is among the special purposes of my present invention to provide a chair which

may be tilted backwardly to any desired degree for the purpose of reclining therein, and in connection therewith to afford a simple and durable and efficient means for the rear legs or supports of the chair to be 60 shifted or inclined rearwardly in accordance with the degree of tilting of the chair body. It will be understood however that while I have mentioned my invention as applied to chairs and will hereafter describe a chair 65 constructed in accordance therewith, the invention is equally well adapted to be applied to settees, couches, or similar articles of furniture used for similar purposes.

Referring to the drawing I show a chair 70 structure of the usual type comprising a back portion 1, arm rests 2, and a seat structure 3, all rigidly secured to each other, and the front legs 4 being likewise rigidly secured to the seat 3. The rear legs 5 are 75 secured to a strip 6, which strip is pivotally secured to the seat 3, for example, by means of the hinge 7 to allow the legs 5 to move rearwardly when the chair is tilted and thereby prevent the chair from turning 80 over from its tilted position. Secured to the under surface of the seat 3 is a bracket 8 provided with an inclined groove 9, which groove is provided with a plurality of indentations 10. To brace the respective front 85 legs 4 relative to each other and to the seat I provide a rod 11 secured to the legs 4 at its ends and passing through the bracket 8 at the portion 12 thereof. It will be seen that this rod is of a substantial V-shape with 90 the apex of the V at that portion which passes through the bracket 8. A similar substantially V-shaped rod 13 with its apex opposed to that of the rod 11 is pivotally secured at its ends to the respective rear legs 95 5 and passes through the bracket 8 at the apex of its V through the slot 9. It will be seen that inasmuch as the legs 5 are pivoted and as the rod 13 passes through the slot 9 of the bracket 8, the legs 5 can be moved 100 backwardly a distance equivalent to the length of the slot 9 of the bracket 8. The depressions 10 from the slot 9 as is shown best in Fig. 2 extend downwardly and rearwardly, or are inclined downwardly in a 105 rearward direction, so that if the rear legs 5 are in their farthest backward position, as indicated by dotted lines, Fig. 2, pressure on the legs in a forward direction will move the legs to assume their upright position 110

thereby facilitating the quick changing of the chair's position from an inclined one to an upright one. When the legs are tilted backward it is obvious that the rear end of 5 the seat 3 drops in proportion to the distance the rear legs have moved, thereby regulating the degree of tilting of the chair. When the chair is in its upright position as shown in Fig. 2, to drop it to any one of its 10 tilted positions upward pressure, say, by the foot, on the rod 13 disengages the rod from the depression 10 of the slot 9 and causes the rod to raise to the slot 9 and thus it can be dropped to any desired notch or 15 depression 10 according to the desire.

While I have shown in the illustration of one embodiment of my invention a chair of wood I wish it to be understood that the chair, or settee, or the like, may be made of 20 any desirable material, for example, it is an exceedingly compact and efficient structure for a steel or other metal chair; likewise, while I have shown the bracket 8 as being provided with three positions of tilting, it 25 is to be understood that any desired number of tilted positions may be supplied, and also that any desired degree of tilting may be secured by ordinary changes in detail of the bracket, such as the degree of slant of the 30 slot 9, the number of depressions 10, which changes of detail will readily occur to those skilled in the art without departing from the spirit or scope of my invention as defined in the claims; I also wish it to be understood 35 that many other changes in detail will readily occur to those skilled in the art without departing from my invention; therefore, what I claim as new and useful, and of my own invention, and desire to secure by 40 Letters Patent, is,—

1. The combination with a seat, a back, and front support rigidly secured together, a rear support pivotally connected to said seat, and a single bracket carried beneath 45 said seat at the approximate center thereof and adjustably connected to said rear support for controlling the degree of pivotal movement thereof relative to said seat.

2. The combination with a seat, a back 50 and front legs rigidly secured together, rear legs pivotally carried by said seat, a bracket carried beneath said seat, and an adjustable connection between said bracket and said rear legs, and a rigid connection between 55 said bracket and said front legs.

3. The combination with a seat, a back and front legs rigidly secured together, rear legs pivotally carried by said seat, a bracket carried beneath said seat, said bracket provided with an upwardly inclined slot, and a 6 brace connecting said rear legs and passing through said slot.

4. The combination with a seat, a back and front legs rigidly secured together, rear legs pivotally carried by said seat, a 6 bracket carried beneath said seat, said bracket provided with a longitudinally extending slot, and a connection between said rear legs and said bracket slidably located in said slot.

5. The combination with a seat, a back and front legs rigidly secured together, rear legs pivotally carried by said seat, a bracket carried beneath said seat, said bracket provided with an upwardly extending slot having a plurality of rearwardly extending 71 depressions therein, and a brace connecting said rear legs and passing through said slot.

6. The combination with a seat, a back and front legs rigidly secured together, rear legs pivotally carried by said seat, a bracket carried beneath said seat, said bracket provided with a longitudinally extending slot having a plurality of rearwardly extending 80 depressions therein, and a connection between said rear legs and said bracket slidably located in said slot.

7. The combination with a seat, a back and front legs rigidly secured together, rear legs pivotally carried by said seat, a bracket carried beneath said seat, said bracket provided with an upwardly extending slot having a plurality of rearwardly extending 89 depressions therein extending downwardly and rearwardly, and a brace connecting said rear legs and passing through said slot.

8. The combination with a seat, a back and front legs rigidly secured together, rear legs pivotally carried by said seat, a bracket carried beneath said seat, said bracket provided with a longitudinally extending slot having a plurality of rearwardly extending 98 depressions therein extending downwardly and rearwardly, and a connection between said rear legs and said bracket slidably located in said slot.

In testimony whereof I have hereunto set my hand on this 14th day of August, A. D. 1917.

HAROLD ROWNTREE.
